(57) **CLAIM**

The ornamental design for an accessory assembly for a bicycle handlebar, as shown and described.

DESCRIPTION

FIG. 1 is a front, right, top perspective view of an accessory assembly for a bicycle handlebar in accordance with our new design;

FIG. 2 is a rear, left, top perspective view of the accessory assembly for a bicycle handlebar of FIG. 1;

FIG. 3 is a left side view of the accessory assembly for a bicycle handlebar of FIG. 1;

FIG. 4 is a right side view of the accessory assembly for a bicycle handlebar of FIG. 1;

FIG. 5 is a top view of the accessory assembly for a bicycle handlebar of FIG. 1;

FIG. 6 is a bottom view of the accessory assembly for a bicycle handlebar of FIG. 1;

FIG. 7 is a front view of the accessory assembly for a bicycle handlebar of FIG. 1;

FIG. 8 is a rear view of the accessory assembly for a bicycle handlebar of FIG. 1;

FIG. 9 is a front, right, top perspective view of the accessory assembly for a bicycle handlebar of FIG. 1, the accessory assembly for a bicycle handlebar being in the deployed configuration;

FIG. 10 is a front, left, bottom perspective view of the accessory assembly for a bicycle handlebar of FIG. 1, the accessory assembly for a bicycle handlebar being in the deployed configuration;

FIG. 11 is a front, right, top perspective view of the accessory assembly for a bicycle handlebar of FIG. 1, the accessory assembly for a bicycle handlebar being shown in an exemplary bicycle handlebar tube; and,

FIG. 12 is a front, right, top perspective view of the accessory assembly for a bicycle handlebar of FIG. 11, the accessory assembly for a bicycle handlebar being in the deployed configuration.

The broken lines immediately adjacent shaded areas represent boundary lines of the claimed design. The other broken lines are directed to environment and are illustrative only. The broken lines form no part of the claimed design.
